(57) **CLAIM**

The ornamental design for a miter saw, as shown and described.

DESCRIPTION

FIG. 1 is a front top perspective view of a miter saw in accordance with our new design;

FIG. 2 is a rear bottom perspective view of the miter saw in accordance with our new design;

FIG. 3 is a front elevational view of the miter saw in accordance with our new design;

FIG. 4 is a rear elevational view of the miter saw in accordance with our new design;

FIG. 5 is a top plan view of the miter saw in accordance with our new design;

FIG. 6 is a bottom plan view of the miter saw in accordance with our new design;

FIG. 7 is a right side elevational view of the miter saw in accordance with our new design; and

FIG. 8 is a left side elevational view of the miter saw in accordance with our new design; and,

FIG. 9 is a rear top perspective view of the miter saw in accordance with our new design illustrating a state in which rechargeable batteries are attached to the miter saw.

The broken line showing of environment structures in the drawings forms no part of the claimed design. The portions within the broken line form no part of the claimed design. The drawings include gray-scale shading which represents contour, not surface ornamentation or any particular color. The blade guard of the miter saw is transparent.

1 Claim, 9 Drawing Sheets
